Attorney.

UNITED STATES PATENT OFFICE.

LOUIS ROTH, OF NEW YORK, N. Y., ASSIGNOR TO STERLING BRONZE COMPANY, OF NEW YORK, N. Y., A CORPORATION OF NEW YORK.

OPERATING MEANS FOR SASH ADJUSTERS.

1,408,908.

Specification of Letters Patent.

Patented Mar. 7, 1922.

Application filed August 5, 1921. Serial No. 489,955.

To all whom it may concern:

Be it known that I, LOUIS ROTH, a subject of Austria Hungary, residing at the city of New York, county of Bronx, and 5 State of New York, have invented a certain new and useful Operating Means for Sash Adjusters, of which the following is a specification.

This invention is an operating means for 10 a sash adjuster, the same being adapted, more particularly, for use on the interior of an automobile body for raising or lowering the sash-window therein, although it is to be understood that the invention is not 15 restricted to this special use for the reason that it may be applied for adjusting sashes in other structures.

The object of the invention is to facilitate 20 the attachment of the operating device to the surface in a manner to harmonize with the upholstery usually provided as a lining within the car body, and to produce a simple, efficient and economical construction adapted to be assembled so that all parts 25 except the operating handle are concealed from view.

With these ends in view, the invention embodies a base provided with a hub, a shaft-actuator in the form of a bushing mounted 30 for free rotation within said base and the hub thereof, an operating member screwed on the shaft-actuator bushing for rotation therewith, and means for detachably locking the operating member and the shaft actuator 35 bushing for conjoint action.

Other functions and advantages of the invention will appear from the following description taken in connection with the accompanying drawings, wherein—

0 Figure 1 is an elevation of my operating means for a sash adjuster applied to the upholstery within the body of an automobile.

5 Figure 2 is a vertical section on the line 2—2 of Figure 1.

Figure 3 is a transverse cross section on the line 3—3 of Figure 2.

In order that others skilled in the art 0 may understand my invention, I have shown it in connection with a body of an automobile, wherein A is a part of a door, wall or other surface, and B is the upholstery applied as usual to constitute a lining for the interior surface of wall A. It is usual 5 to provide an opening a in the wall for

the accommodation of a shaft C which carries a spool c on which is adapted to be wound suitable means whereby the sash may be raised or lowered by the rotary motion of said shaft; but as the sash and the means 60 to be operated by or from the shaft C constitute no part of this invention, I have not considered it necessary to further describe nor to illustrate such ordinary sash-operating means.

D is the base attached to the wall so as to be concealed, for practical purposes, by the upholstery B. Said base is in the form of a metal part comprising an apertured plate provided with a hub d extending outwardly from the plane of said plate. The hub d is formed with a male screw thread d' next to one face of the plate, but on the interior, said hub is provided with an opening of circular cross section, see Figure 3. 75 The apertured plate of the base is applied into contact directly with wall A, and rearwardly of the upholstery so as to be concealed thereby, the opening in hub d being in alignment or register with the wall opening a, see Figure 2, and this plate is secured fixedly to the wall by suitable means, such as screws d², which pass through apertures in the base plate and are embedded in said wall.

E is the bushing rotatable within the base and the hub thereof. Said bushing exceeds the hub in length so that in the operative position of the bushing within the base one end portion of the bushing is flush with 90 the base, whereas the other end portion of said bushing protrudes beyond the corresponding end of the hub, see Figure 2. Said protruding end of the bushing is reduced externally in diameter and provided with a 95 male thread at e, said threaded part of the bushing being provided with a longitudinal recess e', the wall of which is threaded. The bushing is provided with an opening f the cross section of which is square, or 100 of other polygonal shape, see Figure 3, and into this square opening of the bushing is received a square or polygonal part C' of the shaft C, whereby the bushing is coupled to the shaft for imparting rotative movement thereto.

F is the operating member in the form of a crank arm provided at one end with a sleeve F', said sleeve being internally threaded for the purpose of screwing it upon 110

the male threaded part *e* of the bushing so as to operatively attach the operating member to the bushing for conjoint rotation of the parts *E F*. The sleeve *F'* is reduced in diameter externally to produce an external shoulder *f'*, said reduced part of the sleeve extending into the hub *d* of the base member and being free to rotate therein, and the shoulder *f'* being positioned for abutting contact with the hub. The bore of the sleeve *F'* is enlarged and threaded at *g* to enable a cap *G* to be screwed into the sleeve and form a finish for the operating member, and within the chamber formed by the threaded part *g* is encased a coiled spring *G'*, the tension of which is applied to the cap for arresting rotary motion thereof relatively to the operating member. In the inner threaded surface of the sleeve is provided a recess *h*, the wall of which is threaded, and in screwing the sleeve of the operating member upon the male threaded part of the bushing, this recess *h* of the sleeve is brought into register with the groove *e'* of the bushing the said registering recesses *e' h* forming a threaded socket into which is screwed a lock screw *H*, the latter acting to make the operating member *F* fast with the bushing and to prevent the sleeve *F'* of said operating member from becoming unscrewed and detached from said bushing.

J is a collar screwed upon the threaded part *d'* on the hub of the base, said collar being positioned for clamping the upholstery *B* between the base and the collar, thus confining the upholstery in snug relation to the adjuster and imparting a desirable finish to the appearance of said adjuster with respect to the upholstery.

To apply the operating device adapted to be used for imparting movement to the sash adjusting mechanism, the shaft *C* is inserted into opening *a* of the wall for 45 the square end *C'* to extend through the upholstered, whereas the spool *c* lies rearwardly of the wall. The bushing is fitted into the base, and said bushing and base are positioned for the base to be in contact 50 with the wall, whereas the bushing slips over the squared part of the shaft. The base is secured by the screws to the wall, the upholstery *B* is adjusted over the base so as to leave the hub *d* protruding, and collar *J* is screwed upon threaded part *d'* of the base for confining the upholstery in secure relation to the base and to impart a desirable finish to the adjuster.

The operations described are performed 60 without reference to the operating member,

but to complete the assemblage the sleeve *F'* is screwed on the bushing until stopped by the contact of shoulder *f'* with the end of the hub, the lock screw *H* is now inserted for locking the handle to the bushing, spring *G'* is inserted into the sleeve of the operating member, and cap *G* is screwed into sleeve *F'*, all as shown in Figure 2.

It is preferred to attach a knob to the free end of the crank arm *F*, as shown 70 in Figure 2. To this end, a stem *I* is provided with a thread *i* and a flange *i'*, the threaded part of the stem being screwed into an opening tapped into the end of arm *F*, and said stem being locked to the arm by 75 a lock screw *j*. A roller sleeve *I'* is fitted loosely on the stem so as to be free to turn loosely thereon, said sleeve being confined against sliding movement by and between the flange *i'* and the face of the arm *F* 80

Having thus fully described the invention, what I claim as new and desire to secure by Letters Patent is:

1. In an operating device of the class described, the combination with a base having 85 means for securing it fixedly in position, and a shaft member, of a bushing rotatably mounted in the base, said bushing having locking engagement with the shaft member, and an operating member having a fixed 90 connection with said bushing, whereby the base and the bushing may be assembled and applied independently of the operating member.

2. In an operating device of the class de- 95 scribed, the combination with a base and a shaft member, of a bushing rotatably positioned within the base and operatively connected with the shaft member, said bushing having a threaded part, an operating member attached to said threaded part of the bushing, a lock screw co-operating with the bushing and the operating member, and a cap attached to the operating member for concealing the lock screw. 100

3. In an operating device of the class de- 105 scribed, a base member provided with a threaded hub, means for fixedly attaching the base member to be concealed by the upholstered, a collar screwed on the hub and 110 clamping the upholstery between the base member and itself, a bushing rotatably fitted in the base member and the hub, a shaft coupled to the bushing, and an operating member having a threaded connection with 11 the bushing and free from direct attachment to the shaft.

In testimony whereof I have hereto signed my name this 30 day of July, 1921.

LOUIS ROTH.
